UNITED STATES PATENT OFFICE

THEODOR J. C. SCHIRRMACHER, OF OAKLAND, CALIFORNIA

LIQUID DISPENSER

Application filed July 27, 1929. Serial No. 381,541.

The present invention relates to improvements in liquid dispensers, and has particular reference to gasoline dispensers adapted to be used in service stations and garages. The principal object of the invention is to provide a measuring device that is to be used in dispensing gasoline or other combustible fluids into motor vehicle supply tanks or containers used in combination with engines adapted to use combustible fluids. The dispenser I provide is to be of the air pressure type and to be so constructed as to reduce to a greater degree the possibility of explosion in using such dangerous fluids.

Another object is to provide a novel combination of cooperating elements enabling one to place the container beneath the surface of the ground and efficiently operate the dispenser by extended operating means.

A further object is to provide a gasoline dispenser having in combination an exhaust mechanism for catching vapors and gases rising from the container into which the gasoline is dispensed and discharging them at some distant place so that there is no possibility of the gases or vapors being ignited.

It is particularly proposed to use for this purpose a container that may be made of metal or other suitable nonbreakable material from which gasoline may be dispensed by air pressure bearing on the surface of the gasoline in said container, while a gauge surrounds the container and a float riding on the fluid has an indicator associated therewith which allows the lowering of the float to be observed so that the purchaser of the gasoline can watch the amount measured out.

Other objects and advantages of my invention will appear as the specification proceeds.

The preferred form of my invention is illustrated in the accompanying drawing, in which

Figure 1 shows a front elevation of my measuring device;

Figure 2, a vertical section taken along the line 2—2 of Figure 1;

Figure 3, a horizontal section taken along the line 3—3 of Figure 1;

Figure 4, a detail view of the upper end

of the gauge assembly taken along the line 4—4 of Figure 1, and

Figure 5, a side view showing a three way valve as seen from line 5—5 of Figure 1.

In its preferred form, my device comprises a cylindrical container 1, which is to be placed at a desired distance under the surface of the ground 1'; and held in position by a suitable stand 2.

An intake pipe 3, provided with a check valve 4 extending through the top 5 of the container, may be connected to a gasoline supply source. On the side of the container, an overflow pipe 6 is connected and is so disposed as to catch any gasoline that flows over the guard 7. The overflow pipe is connected to a return pipe 8; the latter conduit carries all the overflow to the general reserve tank. Between the overflow pipe and the return pipe, I place a valve 9, which can be operated by a wheel 10. A pipe 11, extending into the container, is affixed to the top 5. This pipe carries a three-way valve 14, to which a pressure-carrying conduit 12 is connected for carrying air pressure into the tank. A revolvable handle 15 is attached to the valve for operating the same. Above this valve is provided a vent pipe 16 for carrying off gas fumes and to relieve the pressure from the tank when it is necessary. A stop member 17, for the operating handle, is mounted on a support 18, the latter being held in position by the pipe 11. The member 17 is revolvable on the pin 19, so that it may be swung from its operative position as a stop when its function is not desired.

From Figure 5 it can be seen that when the handle is in an upright position, air pressure enters the container 1. When the handle is turned through a quarter of a turn, the opening to the conduit 12 is closed while communication is established between the tank and the atmosphere. Should it be desired to keep pressure in the tank, but at the same time cut the latter off from the pressure supply, it is necessary to turn the handle only one-eighth of a complete turn. A stop 17 is swung into operative position to prevent further movement of the handle after making one-eighth of a turn. The stop is swung

out of position when the handle is swung through a quarter of a turn.

A discharge pipe 20 for the gasoline is carried by a member 21.

5 The latter member is provided in order to extend the operating mechanism above the surface of the ground and also to provide a way in which the valve 22, which is connected to the discharge pipe, may be raised out of 10 the container. In order to perform this operation, the plate 23 need only to be freed from the member 21 by removal of the stud bolts 23'. At the bottom of the valve 22, I provide a lever 22' pivoted at 24, which is attached to the valve stopper. At one end of the lever, a rod 24' is connected. This rod is extended through the opening 25 through 15 the pipe 21 and the plate 23. At this point, a packing gland 26 is placed over the rod. I 20 provide a spring 27, having one end resting against the packing gland and the other end against a member 28, the latter being fixed on the rod 24'. By the use of this yielding means, the valve 22 is held normally in a 25 closed position. A pipe 29 encircles the end of the rod 24' and an alined rod 30 leaving a gap 31 between the two rods. The rod 30 is 30 connected to a valve 32, similar to the one disposed in the bottom of the container. On 35 this member 30, an adjusting means 30' is provided, which allows the width of the gap 31 between the two rods 24' and 30 to be adjusted.

The valve 32 in its normal position is held 35 open by a spring 33, having one end fixed to a clamp 34 and the other to an arm 35 extending from the rod 30.

Two clamping members 37 are fixed to the 40 pipe 20 and one of them has the plate 38 pivoted thereto, which latter has a handle 36 extending therefrom by means of which the plate may be operated. The latter is connected through a pin 39 and a vertical member 35' with the arm 35, so that when the 45 handle is swung upward, the rod 30 is depressed for closing the valve 32.

As the rod descends, it strikes the rod 24' and opens the valve 22 in the bottom of the tank.

50 It will be seen from this construction that normally the upper valve 32 is held open by the spring 33 and the bottom valve 22 is held closed by the spring 27. The pipe 20 is normally filled with gasoline. When the handle 55 36 is pressed upward, the rod 30 is forced down for closing the valve 32, so that no gasoline may escape therethrough during the dispensing operation. During the latter part of this movement, the rod 30 operates the rod 24' 60 and thereby opens the valve 22. Gasoline is now discharged until the operator releases the handle 36, which causes both springs to actuate their respective valves for closing the bottom valve and opening the top valve. But 65 it should be noted that the rod 24' has a

shorter distance to travel in returning to normal than the rod 30 and that therefore the bottom valve closes slightly before the top valve opens so that the pressure is taken off prior to the opening of the top valve.

70 By keeping the valve 32 open when the pressure from the tank is cut off from the discharge pipe 20, no vacuum is allowed to form in the T coupling 41 or the discharge pipe 42. It is to this latter member that I connect a 75 discharge nozzle 43.

It is also to be noted that in order to use my method of discharging gasoline and at the same time insure an exact measure, a check valve 40 is provided, which operates to allow 80 no return of gasoline to the container after it has been forced up past the stopper of the valve. It should also be noted that there are no valves between the container 1 and the storage tank through which it might be possible 85 for a leakage of gasoline.

To minimize the possibilities of explosion, the discharge nozzle 43 has a pipe 44 disposed 90 therein to carry off the gas vapors and fumes of the automobile tank or any container that the gasoline is dispensed into. The pipe 44 is connected to the vent pipe 16 by the T coupling 45.

A gauge 46 that is operated by a float 47 is disposed in a desired position above the 95 container 1. In Figure 4, I have pictured my novel construction for making the gauge a nonleakable one. In view of the fact that the expansion and contraction of glass and metal are different, it is necessary to provide a yielding means to hold the washer 47' tight against the glass 48. I obtain this object by providing a bolt 49 having an enlarged 100 portion 50 to engage with a spring 51. A metal washer 52 engages with the other end of the spring. Hence, it can be readily seen that by adjusting the bolt 49 and making it fast by a lock nut 53 any desired pressure may be obtained and at the same time the expansion and contraction of the glass and metal does not cause the air to leak by the washer 105 47'.

110 While I have shown only the preferred form of my invention, I wish to have it understood that various changes or modifications 115 may be made within the scope of the claims hereto attached without departing from the spirit of the invention.

I claim:

1. In a liquid dispensing device of the character described, a tank having an outlet conduit extending thereinto, pressure means for discharging liquid therethrough, a valve for the conduit within the tank, a second valve for the conduit outside of the tank for venting the conduit and a common control for both valves.

120 2. In a liquid dispensing device of the character described, a tank having an outlet conduit extending thereinto, pressure means for 125

130

discharging liquid therethrough, a valve for the conduit within the tank, a second valve for the conduit outside of the tank for venting the conduit and a common control for both valves, including means for opening one of the valves after the other.

5 3. In a liquid dispensing device of the character described, a tank having an outlet conduit extending thereinto, pressure means for discharging liquid therethrough, a valve for the conduit within the tank, a second valve for the conduit outside of the tank for venting the conduit, a common control for both valves comprising two alined and normally spaced actuating rods for the two valves and means for operating one of the rods for first actuating its valve and then the other rod which actuated the second valve.

10 4. In a liquid dispensing device of the character described, a tank having an outlet conduit and pressure means for discharging therethrough and a gauge for said tank comprising a tube rising from the tank and slotted through a section thereof, a glass tube within 15 said section, a float in the tank having a rod extending into the tube with a pointer movable in the glass tube for showing the level of the liquid within the tank, a removable cover for the glass tube and spring means for 20 seating the same.
